UNITED STATES PATENT OFFICE.

THOMAS P. KIRBY, OF CANON CITY, COLORADO, ASSIGNOR OF ONE-FOURTH TO J. G. BLAKE, OF CANON CITY, COLORADO.

RAILROAD-TIE.

1,193,398.

Specification of Letters Patent. Patented Aug. 1, 1916.

Application filed April 2, 1915. Serial No. 18,791.

To all whom it may concern:

Be it known that I, THOMAS P. KIRBY, a citizen of the United States, residing at Canon City, in the county of Fremont and State of Colorado, have invented certain new and useful Improvements in Railroad-Ties, of which the following is a specification.

This invention relates to railroad ties and 10 has particular reference to metallic ties of that type, in which cushioning elements are used for minimizing vibration of the rolling stock which passes therover.

An object of the invention is to provide a 15 novel formation of tie, with which specially designed rail fastening means coact, to prevent lateral thrust of the rails, even should undue pressure be exerted thereon.

Another object of the invention is to associate a reinforcing medium with the tie, in 20 order to reinforce the metallic tie structure or casing, and to hold the cushioning elements from displacement.

Other objects as well as the nature, characteristic features and scope of my invention 25 will be more readily understood from the following description taken in connection with the accompanying drawings and pointed out in the claims forming a part of this 30 specification.

Referring to the drawings: Figure 1 is a side elevational view of a tie constructed in accordance with my invention, illustrating the application thereof, Fig. 2 is a top plan 35 view of a pair of ties constructed in accordance with my invention, and illustrating the application thereof, Fig. 3 is a longitudinal sectional view taken on the line 3—3 of Fig. 2 and looking in the direction of the arrows, 40 a portion thereof being broken away to disclose details, Fig. 4 is a sectional view taken on the line 4—4 of Fig. 3 and looking in the direction of the arrows, showing to advantage the plastic reinforcing composition and 45 one of the rail fastening means, Fig. 5 is a detail enlarged perspective fragmentary view of one of the rail holding means *per se* showing its application to a rail, the latter being shown in dotted lines.

In the drawings wherein is illustrated the preferred embodiment of this invention, a pair of rails 1 are shown in order to illustrate the application of my invention.

My improved tie structure is designated 2 55 and embodies a metallic casing or shell of

the usual configuration, which is provided with openings 3 in its upper face, one of the walls of each of the openings 3 being arcuate to permit the insertion of an implement therebetween and the rail 1, to facilitate removal of the latter from the recess 3. The tie 2 is of the usual configuration and is hollow throughout its entire length, having a portion of its upper face removed, as indicated at 4, through which is inserted a 60 plastic composition, preferably concrete, as indicated at 5, the latter lying flush with the upper marginal edges of the opposite sides of the shell or casing 2, so as to reinforce the casing. Portions of the reinforcing composition 5 are removed, to provide recesses 6. Ears 7 are formed by extending the inner face of each side of the tie, above said openings for a purpose more fully herein- 65 after described.

Detachably mounted in the shell or casing 2 and in proximity to the opposite ends of the latter are rail fastening means 8, each of the latter in the present instance comprising a bolt provided with a threaded shank 9, the latter having a head on its upper terminal which has a portion 10 projecting laterally therefrom for engagement with the base flange of the rail 1. The fastening means 8 are arranged in such close proximity to the lateral margins of the shell or casing 2, that it is necessary to provide reinforcing ribs 11 on the casing, in order to prevent casual displacement of said means should undue pressure be exerted thereon. 90 Both of the threaded shanks 9 depend into corresponding recesses 12 in the opposite lateral margins of the casing 2, whereby access is gained to a nut 13 on each of said threaded shanks 9, thereby positively locking said fastening means from displacement.

Reinforcing blocks 14 are mounted in the opposite ends of the shell 2, in the present instance being preferably made of wood, in view of their inherent shock absorbing characteristics, likewise in view of their inexpensive nature. The blocks 14 are arranged subjacent the openings 3 in the top of the shell and are provided with recesses in their upper faces, so as to receive the base flanges 105 of the rails 1, said flanges being thereby arranged below the upper plane of the tie, so as to minimize the possibility of lateral movement of the rail. The inner terminals of the cushioning block 14 abut the plastic 110

composition 5, the latter thereby bracing the blocks from relative movement toward each other, said blocks being held from displacement in opposite directions, the recesses 5 formed in the upper faces thereof being engaged by the rails. The openings 3 in the top of the shell 2 are relatively larger than the base flanges of the rails 1, thereby permitting access to be had beneath the rails, 10 for extracting the same from the recesses in the face of the shell, at the same time permitting access to be gained to the blocks 4, in order to expedite removal of the same should they be rendered worn unsuitable for use.

15 As previously stated, the fastening means are utilized for preventing lateral thrust of the rails 1 toward the opposite ends of the shell or casing 2, while lateral thrust of the rails in a counter direction is precluded in 20 view of rail fastening means generally designated 15. The means 15 embodies a gravity latch member 16, one end of which has a portion thereof removed, to conform to the contour of the base flange of the rail, and 25 adapted for engagement with the latter. The opposite end of the gravity latch 16 is pivotally connected to one end of a bolt 17, the opposite end being screw-threaded and engaged through an ear 7 in the upper face 30 of the casing 2, as advantageously illustrated in Fig. 3. A nut 18 is threaded on each of the bolts 17, whereby the latter are movable in a vertical plane in the casing, so as to actuate the gravity latch 16 into engagement 35 with or out of engagement from the base flange of the rail 1. A bracing rib 19 is formed on the inner face of the shell or casing 2, in proximity to each of the rail-bracing means 15, for abutment with one end of 40 each of the gravity catches 16, so as to throw the latter more snugly into engagement with the base flange of the rail 1, by increased pressure upon the nut 18. It is, of course, obvious that the lower end of the bolt 17 45 floats in the casing so as to be freely movable relative to the rails 1.

It will be noted that the upper face of the shell 2 is provided with inclined cut-out portions 20 therein, adjacent the latches 16, 50 so as to permit movement of the latter in a vertical arc, whereby removal of the rails 1 from the shell is expedited.

In operation therefore, it is of course, understood that the rails 1 are first arranged upon the cushioning blocks 14, after which 55 the rail-fastening means 8 are snugly engaged with the base flange of the rail, by the exertion of pressure upon the nuts 13. Pressure is then exerted upon the nuts 18, so as 60 to operate the catches 16 into snug engage-

ment with the base flanges with which the rails 1 on the opposite side from that of the means 8 engage, thereby precluding possibility of the rails being laterally thrust in either direction. When it is desired to remove the rails from the shell or casing 2, the nuts 13 and 18 are, of course, removed from their respective bolts, to permit removal of the rail-fastening means, and disengagement of the latches 16. A suitable instrument 65 may then be inserted beneath the rail 1, through the openings 3 in the top of the shell, when it is desired to raise the rail out of engagement with the casing.

It will be understood that the above description and accompanying drawings comprehend only the general and preferred embodiment of my invention and that various minor changes in details of construction, proportion and arrangement of parts, may 70 be made within the scope of the appended claims without sacrificing any of the advantages of my invention.

Having thus fully described my invention what I claim as new and desire to secure by 85 Letters Patent is:

1. A rail fastening means including the combination, with a tie structure, of means mounted therein and engaging one side of the base flange of a rail to hold the latter 90 from displacement in one direction, a floating clamping bar positioned in said tie and having a working end engaged with the opposite side of said base flange, a stationary member within said tie, the opposite end of 95 said floating clamping bar being engaged with said stationary member, and means connected with said floating clamping bar for adjusting the latter between said stationary member and said rail. 100

2. A rail fastening means including the combination with a tie structure, of means mounted on the tie for engagement with one side of a rail base flange, an inclined stationary member within said tie, a clamping 105 bar engaged with said inclined stationary member and having a working end engaged with the opposite side of the base flange, means to prevent upward movement of the working end of said clamping bar, and 110 means pivoted to said clamping bar to tighten the latter against said rail base flange.

In testimony whereof I affix my signature in presence of two witnesses.

THOMAS P. KIRBY.
